DESIGN FOR AN INFANT'S DRESSING AND RUBBING TABLE

Eugene M. Elson, Los Angeles, Calif.

Application June 9, 1945, Serial No. 119,987

Term of patent 7 years

(Cl. D33—14)

To all whom it may concern:

Be it known that I, Eugene M. Elson, a citizen of the United States, residing at Los Angeles, in the county of Los Angeles and State of California, have invented a certain new, original, and ornamental Design for Infant's Dressing and Rubbing Table, of which the following is a specification, reference being had to the accompanying drawings, forming part thereof.

Figure 1 is a front view in elevation of the

infant's dressing and rubbing table embodying my new design; Fig. 2 is a view in end elevation of the same; Fig. 3 is a rear view in elevation of the same; Fig. 4 is a top plan view of the same; Fig. 5 is a perspective view of the same.

I claim:

The ornamental design for an infant's dressing and rubbing table, as shown.

EUGENE M. ELSON.
